UNITED STATES PATENT OFFICE.

WILLIAM L. SETTLE, OF MEMPHIS, TENNESSEE, ASSIGNOR TO JAY R. CORBETT, OF MEMPHIS, TENNESSEE.

SPUDDING-SHOE.

1,340,420.

Specification of Letters Patent. Patented May 18, 1920.

Application filed December 23, 1919. Serial No. 347,008.

To all whom it may concern:

Be it known that I, WILLIAM L. SETTLE, a citizen of the United States of America, residing at Memphis, in the county of 5 Shelby and State of Tennessee, have invented certain new and useful Improvements in Spudding-Shoes, of which the following is a specification.

The primary object of the invention is the 10 provision of a spudding shoe adapted for ready positioning upon and removal from a cable by merely changing the positions of the shoe without the necessity of adjusting any parts thereof, the shoe moreover being 15 operatively held against accidental displacement when the device is positioned for use.

A further object of the invention is to 20 provide a spudding shoe possessing great strength and inexpensive to manufacture, the construction being such that the shoe may be instantly positioned for use upon the well cable and removed therefrom at will by merely twisting the shoe itself, the device 25 also furnishing renewable contact faces for the cable insuring long life and ease of operation.

A still further object of the invention is 30 to provide a spudding shoe calculated to exert only the minimum amount of wear upon the cable with which the shoe is used and adapted for ready installation with any 35 rope and cable equipment for well drilling apparatus, the shoe being adaptable for different sized cables of the drill rig.

With these general objects in view and others that will hereinafter appear, the invention will be now fully described.

In the drawing forming a part of this 40 application, like reference characters designate corresponding parts throughout the several views, and

Figure 1 is an elevational view illustrating the invention installed for operation,

45 Fig. 2 is a side elevation of the shoe partly broken away illustrating the well cable in section with the shoe indicated by dotted lines during the operation of attaching the shoe to the cable,

50 Fig. 3 is a front elevation of the invention as shown in Fig. 1 upon an enlarged scale, and

Fig. 4 is a top plan view thereof with the cable broken away.

55 Referring more in detail to the drawing,

my shoe in the main is substantially triangular in form comprising a body 10 having a spool or roller 11 journaled by means of a removable pin 12 at one end of the body 10 and being referred to as the rear end of the 60 shoe at the apex of the triangular formation. The jerk line or rope 13 of the well drilling rigging is attached by means of a loop 14 to the roller 11 in any well known manner whereby movement is imparted to 65 the shoe during the drilling operation.

The forward end or base of the triangular body 10 is arcuate and divided into two similar oppositely positioned sections 15 and 16 with a transverse slot 17 dividing the 70 base portion of the body 10 into sections 18 and 19.

The said sections 18 and 19 are substantially L-shaped in form providing arcuate entrance slots 20 and 21 at opposite sides of 75 the shoe for the sections 18 and 19 respectively, whereby the shoe may be positioned with the body 10 upon the drilling cable 22 by placing the slot 17 over the cable 22 with the shoe substantially horizontal and then 80 turning the shoe with the slots 20 and 21 substantially vertical so that the cable 22 passes through said slots during the turning movement of the shoe. A pull upon the roller end of the shoe then seats the cable 22 85 upon the removable slip or bearing faces 23 provided within the sections 18 and 19.

The slip faces 23 are arcuate for fitting over the base portions 15 and 16 within the sections 18 and 19 respectively while screws 90 24 removably secure the slip faces in their operative positions. The inner bearing sides 25 of the slip faces 23 are preferably grooved for receiving the cable 22 and it will be understood that said slip faces are 95 formed of any suitable material such as steel. From this detailed description of the invention, it will be apparent that the shoe may be instantly positioned upon the cable 22 with the sections 18 and 19 hooked over 100 the cable which is seated within the L-shaped sections upon the removable bearing faces 23 hereinafter noted. The operation of the line 13 as well as the shoe are also apparent, the pin 12 being removable when desired to 105 disengage the roller 11 from the jerk line loop 14. A strong and serviceable spudding shoe is provided combining the advantages of the renewable bearing faces with the ease of placing the shoe in position upon the 110

drilling cable as well as removing the same therefrom.

While the form of the invention herein set forth is believed preferable, it will nevertheless be understood that minor changes may be made therein without departing from the spirit and scope of the invention hereinafter claimed.

What is claimed as new is:

- 10 1. A spudding shoe having a cable bearing surface and further having an entrance opening for a well drilling cable intersecting the bearing surface.
- 15 2. A spudding shoe having a cable bearing surface and further having an entrance opening for a well drilling cable arranged at right angles to the cable bearing surface.
3. A spudding shoe having a divided

bearing surface with an angle slot formed in each side of the shoe.

20 4. A spudding shoe having a divided bearing surface with an angle slot formed in each side of the shoe, the inner ends of the slots being alined to provide a cable entrance opening to the shoe.

25 5. A spudding shoe having a cable bearing surface and further having an entrance opening for a well drilling cable at the outer side of said shoe.

6. A spudding shoe having a cable bearing surface and further having an entrance opening for a well drilling cable extending at an angle to said bearing surface.

30 In testimony whereof I affix my signature.

WILLIAM L. SETTLE.
